United States Patent Office.

IMPROVEMENT IN BOOT AND SHOE IRONS.

JOHN KNOX, OF AUBURN, NEW YORK.

Letters Patent No. 60,198, dated December 4, 1866.

SPECIFICATION.

TO WHOM IT MAY CONCERN:

Be it known that I, JOHN KNOX, of the city of Auburn, in Cayuga county, New York, have invented a new and improved mode of constructing fore-part Irons for smoothing the edges of the soles of Boots and Shoes; and I do hereby declare the following to be a full, clear, and exact description of the same, reference being had to the accompanying drawings, making a part of this specification, and to the letters of reference marked thereon.

The fore-part iron is one of the most essential as well as the most expensive of all the tools requisite to the full equipment of the knight of the bench. Its function is to smooth the edges of the soles of boots and shoes, and when we think how great the number of thicknesses, and know that every varying thickness must be exactly fitted by this iron, we can form some idea how many different sizes of irons will be required for every workman. And when the fact also appears that the iron, when in all respects fitted to the finishing of sewed work, will not answer at all for work that is pegged, it will be seen that to fit the irons to the work would require a very great number. These irons, not unfrequently, cost the workman from thirty to fifty dollars, and after this outlay he not unfrequently finds that he has not, amongst his entire kit, an iron of the right size or width for the thickness of the work he is doing.

Now, the object of this invention is to furnish the craft with one tool at less than one-fourth the expense incurred in either sewed or pegged work, taken separately, that will perform all the functions required in both cases much better than the tool now in use. To accomplish this I make the space between the back and front guards adjustable in such manner that the tool can be set very readily to fit any thickness of soles. I also make my tool double sided, and arrange and adapt one to the use of pegged work, and the other to sewed. By this arrangement all thicknesses of soles, from the thinnest slipper to the thickest boot, whether the same be pegged or sewed, can be finished without any manner of inconvenience to the workman, much better than can be done by any of the tools now in use.

In order that others skilled in the art may know how to make and use my invention, I will proceed to describe its construction and mode of operation.

Figure 1 is a section taken through the entire tool.

Figure 2 is one of the outside guards, with the curved plate attached and making a part of the same.

Figure 3 is the other.

Figure 4 is an edge view of the tool with a part of the handle removed.

In fig. 1, A is the handle; B is the back guard for sewed work. For this purpose, this guard requires to be much shorter from the bed-piece, C, than is required for work that is pegged. D is the front guard for sewed work; this guard is required to project some further from the bed C, of the iron, than is required for work that is pegged. F is an elevation thereof. The curved bed-piece C is a part of the double guard piece K, and both are made of one piece of metal. The bed C passes through the space 1, and the curved plate G through the space 2. The partition between the two figures is but a continuation of the plate H, fig. 3. E is the back guard for pegged work, and on this account extends up further from the bed C than the opposite one. I is the front guard for pegged work. J is an elevation of the plate. The bed-piece C, and the curved plate H, connected with and forming part of the plate F, both extend through the space K, in the plate J. The double guard piece K extends into the handle A, and through the portion of it included between the letters L M, is cut a screw-thread to receive the bolt O. This bolt is made fast to the section P, of the handle A. By turning the portion, P, of the handle A backward, both the front guards are freed, and may be set by the workman to fit any thickness required.

The essence of my invention consists in making the space between the back and front guard adjustable by moving the front guard on the bed-piece C; and of combining the short back guard with the long front guard for sewed work, with the long back guard and short front guard in the same tool for pegged work.

Having above described the construction and mode of operating my invention, what I claim as new, and wish to secure by Letters Patent, is—

1. Adjusting the space between the back and front guards, substantially in the manner and for the purpose set forth.
2. The combination of the short back guard and long front guard, with the long back guard and short front guard, substantially in the manner and for the purpose above specified.
3. In fore-part irons holding the front guards in their place by means of a screw operated through the handle as above set forth.

JOHN KNOX.
